CLAIM

The ornamental design for a snap-on protective cover, as shown and described.

DESCRIPTION

FIG. 1 is a perspective view of a snap-on protective cover showing my new design;

FIG. 2 is a top view thereof;

FIG. 3 is a cross sectional view thereof taken along line A-A of FIG. 2;

FIG. 4 is a front view thereof, the rear view being identical;

FIG. 5 is a cross section view thereof taken along line B-B of FIG. 4

FIG. 6 is a right side view thereof, the left side view being identical;

FIG. 7 is a bottom view thereof;

FIG. 8 is a perspective view of the snap-on protective cover coupled to a capacitor; and,

FIG. 9 is a front view of the snap-on protective cover coupled to a capacitor.

The broken lines shown represent environmental subject matter and form no part of the claimed design.
